United States Patent Office

Des. 223,311
Patented Apr. 4, 1972

223,311

SMOKING PIPE OR SIMILAR ARTICLE

William Geiser, 903 Alto St., Monrovia, Calif. 91016

Filed May 4, 1971, Ser. No. 140,313

Term of patent 14 years

Int. Cl. D27—02

U.S. Cl. D85—8

FIG. 1 is a perspective view of a smoking pipe or similar article, showing my new design;

FIG. 2 is a top view thereof; and

FIG. 3 is a rear view thereof.

I claim:

The ornamental design for a smoking pipe or similar article, as shown.
